UNITED STATES PATENT OFFICE

CLARENCE B. HARBISON, OF LIMA, OHIO, ASSIGNOR TO THE OHIO STEEL FOUNDRY COMPANY, OF LIMA, OHIO, A CORPORATION OF OHIO

TENDER FRAME STRUCTURE

Application filed January 27, 1928. Serial No. 249,823.

This invention relates to improvements in tank car constructions and more particularly to tender frame and tank constructions, although not limited to such use.

As heretofore constructed, locomotive tenders have been provided with cast steel main frames upon which the tank body is directly supported, and more recently such main frames have been more or less skeletonized so as to include only a centrally disposed longitudinal beam and transversely disposed bolsters and sills formed integral therewith, upon which the tank body is supported.

In carrying out my invention I provide an improved construction of tender frame and tank body of the skeletonized type above described, wherein a portion of the frame projects upwardly into the tank body and the bottom plates of the tank are connected directly to the sides of the frame members considerably below the top thereof, so that said frame members project into and form a part of the bottom of the tank. This construction therefore provides a simple and effective means of connecting and supporting the tender tank body on its frame, and also permitting the tender body to set lower on the frame with a reduced center of gravity.

Other features of advantage will appear from time to time as the description proceeds.

The invention may best be understood from the accompanying drawings, in which

Figure 1 is a side view of a locomotive tender constructed in accordance with my invention.

Figure 2 is an enlarged fragmentary view of a rear portion of the tank and frame, with a portion of the tank side broken away.

Figure 3 is a fragmentary plan view of the rear end of the tender frame, with the upper half of said frame shown in horizontal section.

Figure 4 is a fragmentary plan view of the front end of the tender frame, with the upper half of said frame shown in horizontal section.

Figure 5 is a fragmentary vertical section taken on line 5—5 of Figure 3.

Figure 6 is a fragmentary vertical section taken on line 6—6 of Figure 4.

Figure 7 is a transverse section taken on line 7—7 of Figure 2, and

Figure 8 is a typical transverse section showing the interior construction of the tank body taken on line 8—8 of Figure 1.

Referring now to details shown in the drawings, the locomotive tender shown in Figure 1 comprises a tank 10, supported on main frame 11 which in turn is supported on trucks 12, 12, which may be of any suitable construction. The tank 10 shown herein is of the usual two-compartment type, the rear compartment 10a being for water and the front compartment 10b for coal.

The main frame 11 consists of a centrally disposed beam or sill 15 and laterally extending bolsters 16 and 17, near the front and rear end thereof, and a rear end sill 18, all preferably cast integral with each other. A pair of diagonal braces 19, 19 connect the center sill 15 with the ends of the rear end sill 18.

The central beam 15 is preferably of hollow box girder construction, and is provided with the usual means for draft connections at opposite ends, which need not be described in detail excepting to point out that the rear end portion 15a of the center sill 15 is offset downwardly below the rear end of the tank 10.

The bolsters 16 and 17 are also of a box girder type but as shown herein are relatively wider than the center sill, and extend almost the full width of the tank body 10, as is best shown in Figures 3, 5 and 6. The top walls 20 of the bolsters are preferably in the same plane as the top wall 21 of the central girder 15. The side walls 22, 22 and end walls 23 of the bolsters are substantially upright and have a horizontal flange or projection 25 along their lower margins, which joins with continuous flanges 26, 26 formed along the side walls 27, 27 of the central beam 15.

The bottom walls 29 of the bolsters 16 and 17 are offset upwardly to form recessed por-

tions 30, 30 which afford additional clearance over the truck bolsters, and for the insertion of side bearings of the usual form (not shown) therebetween as desired.

5 The tank body is built up on the tender frame by riveting or welding horizontally disposed plates 35, 35 along the flanges 25 and 26 of the bolster and central beam respectively. With this construction the upper portions of the bolsters and center frame form a part of the tank bottom, but project substantially above the bottom water line of the tank, as clearly shown in Figures 5, 6, 7 and 8. In the form shown, the bottom 10 plate 35 near the rear end of the tank rests upon the angular braces 19 and end sill 18, and may be secured thereto in any suitable manner, as by welding, riveting or bolting.

Details of construction of the superstructure comprising the tank 10 may vary widely; for instance, in the cross section shown in Figure 8 said tank body is made up of two side walls 38, 38, riveted or welded to upstanding flanges 39, 39 formed integrally with the bottom plates 35, 35. A centrally disposed vertical baffle plate 40 is mounted on the center sill 15, and side baffle plates 41, 41 are connected to the bottom plates 35, 35 and side walls 38, 38. A series 20 of internal braces 42, 42 connect the central and side baffle plates together, said braces preferably being arranged in lines extending diagonally downward toward the center sill 15, so as to afford additional support for 30 the sides of the tank.

I claim:

1. In a tank car, a main frame comprising a longitudinal center sill, transverse bolsters connected therewith, and tank bottom plates 40 secured to said sill and bolsters in a continuous line adjacent their lower edges, and extending laterally therefrom to form with said sill and bolsters the bottom of a tank.

2. In a tank car, a main frame comprising 45 a longitudinal center sill of box girder form, transverse bolsters connected therewith, flanges extending around said sill and bolsters in a continuous line adjacent their lower edges, and tank bottom plates secured 50 to said flanges and extending laterally therefrom to form with said sill and bolsters the bottom of a tank.

3. In a tank car, a main frame comprising 55 a longitudinal center sill of box girder form, transverse bolsters connected therewith, flanges extending around said sill and bolsters in a continuous line adjacent their lower edges, and tank bottom plates secured 60 to said flanges and extending laterally therefrom to form with said sill and bolsters the bottom of a tank, and tank superstructure mounted partially on said bottom plates and partially on said main frame members.

4. In a tank car, an integral main frame 65 casting comprising a longitudinal center sill

and transverse bolsters, both of box girder construction, said sill and bolsters having flanges in a continuous line extending adjacent their lower edges, and tank bottom plates connected with said flanges and extending laterally therefrom to form with said sill and bolsters the bottom of a tank.

5. In a tank car, an integral main frame casting comprising a longitudinal center sill and transverse bolsters both of box girder construction, tank bottom plates secured to said center sill and bolsters in a continuous line adjacent their lower edges to form with said sill and bolsters the bottom of a tank, said bolsters being of less vertical height than said central sill and having recessed portions on their under surfaces to afford clearance for their respective truck bolsters.

Signed at Lima, Ohio, this 23rd day of January, 1928.

CLARENCE B. HARBISON.
